UNITED STATES PATENT OFFICE.

ARTHUR STOCKSTROM, OF ST. LOUIS, MISSOURI, ASSIGNOR TO AMERICAN STOVE COMPANY, OF ST. LOUIS, MISSOURI, A CORPORATION OF NEW JERSEY.

OIL-STOVE.

1,332,775.

Specification of Letters Patent. Patented Mar. 2, 1920.

Application filed September 3, 1919. Serial No. 321,361.

To all whom it may concern:

Be it known that I, ARTHUR STOCKSTROM, a citizen of the United States, residing at St. Louis, State of Missouri, have invented 5 certain new and useful Improvements in Oil-Stoves, of which the following is a specification, reference being had therein to the accompanying drawing.

This invention relates to improvements in 10 oil stoves, and is of the blue-flame type, utilizing a wick from the upper end of which vapor is generated, combined with inner and outer air distributing structures and an embracing elongated chimney, 15 whereby the vapor generated at the wick is converted into an elongated blue-flame extending through the chimney, to be used for cooking purposes.

The primary object of my present invention 20 is to simplify and cheapen the construction of, and to improve the result of the aforesaid type of wick blue-flame oil burners.

Further specific objects of the invention 25 will appear from the following description and disclosure.

In the accompanying drawings.

Figure 1 is a vertical central sectional view of a burner embodying my invention.

Fig. 2 is an enlarged inverted perspective view of the chimney with my improved outer air distributor attached thereto.

Fig. 3 is an enlarged sectional view of one side of the lower end of the chimney 35 with my improved outer air distributor carried thereby.

Fig. 4 is a detached perspective view of my improved inner air distributor.

In carrying out my present improvement, 40 I employ suitable outer and inner wick tubes 1 and 2, between which is located the ordinary wick 3. This wick is provided with the usual perforated sleeve 4, with which a cog wheel, not shown, carried by the wick-raising stem 5, engages, and by means of 45 which the wick is raised and lowered.

A chimney A of my improved burner has a straight vertical lower end 6, and a straight vertical upper end 7, of a diameter relatively 50 smaller than the diameter of the lower end 6, and these two straight walled portions 6 and 7 are connected by an upwardly and inwardly tapered portion 8. As here

shown, the portions 6, 7 and 8, are formed of separate pieces, but it is not essential that 55 these parts be made of separate pieces so far as the operation of my improved burner is concerned.

Located within and attached to the lower end of the chimney is an outer air distributor B, which is attached to the lower extremity of the chimney, in a manner to be explained hereinafter.

A horizontal flange 9 projects outward from the outer wick tube 1, some distance below the upper end of the tube, as shown. This flange may be formed as a part of the outer wick tube 1, or separate therefrom and attached in any suitable manner, without departing from the scope of my invention. In 70 a full-sized burner this flange 9 is approximately three fourths of an inch below the upper end of the outer wick tube 1, and is in a full sized burner approximately one-fourth of an inch wide.

The burner here shown, is of the well-known circular or Argand type, thus producing a circular flame, and the flange 9 extends entirely around the outer wick tube and is imperforate.

In my improved burner, the outer air distributor is composed of only an outer member 10 and an inner member 11, the outer member 10 has at its lower end an outwardly extending horizontal flange 12, the periphery of the flange provided with an upwardly extending lip 13, which is bent inward at several points 14, tightly against the outwardly extended lower end 15 of the portion 6 of the chimney A. By this means, the outer member 10 is connected with and carried by the chimney A. The inner member 11 is a vertical annular flange, which is attached to the portion 6 of the chimney by radially extending spacers 16. These spacers 95 16 have their inner edges provided with one or more lips 17, which pass through the member 11 and bent over upon it and with one or more upwardly extending lips 18, which pass through the member 10, and are 100 bent laterally against it, thus uniting the outer edges of the spacers 16 to the inner side of the outer member 10, and the inner edges of the spacers 16 to the outer face of the member 11.

The outer member 10 has a very slight 105

The outer member 10 has a very slight

outer and inward taper from the flange 12 and has at its upper end 19 a slight curve, which approximates a horizontal portion with its inner end 20 turned or dipped 5 downward. This approximately horizontal portion 19 is provided with a plurality of vertical openings 21, arranged therearound in a circle and located approximately vertically above the upper edge of the inner 10 member 11, while the horizontal flange 12 is provided with a plurality of vertical openings 22, arranged in a circle around the flange, as shown in Fig. 2. The inner member 11 is provided with a plurality of horizontal openings 23, arranged therearound in circular relation slightly above its lower edge. These openings are relatively small and are preferably composed of two rows of 15 openings arranged in staggering relation, 20 which while permitting a proper volume of air to pass through the openings, it provides the air in small currents.

As clearly shown in Fig. 1, the inner member 11 is of a diameter slightly less than 25 the diameter of the flange 9, but greater than the diameter of the outer wick tube 1, which provides an annular chamber 24, surrounding the upper end of the wick tube above the flange 9.

30 The chimney A is provided with a suitable handle, (not shown) by means of which it is readily lifted from the wick-tube for the purpose of permitting ready access to the wick for lighting purposes, or for the 35 purpose of renewing the wick. By reason of this construction, the outer air distributor B is in a sense a part of the chimney, so that when the chimney is removed from the structure, the outer distributor B is re- 40 moved with it, it leaves the wick entirely exposed for lighting or other purposes, making it easy to light the burner. Also by reason of this construction, the weight of the chimney and the outer air distributor 45 B is sustained by the lower edge of the inner member 11, resting on the flange 9, and the inner edges of the lower portions of the spacers 16, are slightly tapered upward, as shown at 25, so that these spacers not only 50 serve to unite the parts of the outer air distributor, as described, but also serve to accurately center the air distributor in respect to the wick, which is absolutely essential for proper operation and to obtain a 55 uniform blue flame throughout the complete circle of the wick. Any appreciable variation out of center of the air distributor in respect to the upper end of the wick, will cause a yellow portion in the blue flame. 60 By accurately centering the outer air distributor, as described, the formation of yellow portions in the blue flame is avoided. This construction accurately positions the inner and outer members in respect to the 65 wick and insures accurate burning.

I am aware that an outer air distributor has been arranged around the upper end of the wick to produce a blue flame, but so far as I am aware this air distributor has not consisted of two members only with the extreme simplicity of my burner.

The chamber 24 between the inner member 11, and the outer wick tube 1 to which fresh air is admitted through the openings 23, provides a surrounding cooling chamber for the upper end of the wick tube and causes an upward current of air in this chamber, which prevents any falling of vapors therein. This upward current of air will flow through the openings 23 into the chamber 24, the primary function of which is to commingle with the vapor at the upper end of the wick to support combustion, but some of it may pass upward through the openings 21 of the outer member 10. The 80 upper portion of the chamber 24 is slightly contracted by an inward annular bend 26 formed in the inner member 11, which will tend to accelerate the flow of air through the chamber 24.

By reason of the construction described, there is an open space between the members 10 and 11 for the entrance of fresh air, for the purpose of cooling the members 10 and 11, and prevent them from over-heating, 90 and the upper end of the member 10 is further cooled by air passing through the openings 21. Furthermore, the air passing through the openings 21 furnishes fresh air to the flame above it, which serves to promote a more perfect combustion. These openings also prevent any dead space over the upper end of the member 10. By reason of this simple construction, there is no un- 100 ventilated passage outside of the wick tube, all of which serves to prevent the burner from overheating, which is one of the faults of this type of burner. Unless the construction is such as to prevent the burner from becoming too hot, the generation of vapor is 110 accelerated to such an extent that it will cause the flame to creep upward and increase beyond its proper height and prevent an accurate regulation unless it is frequently regulated by turning down the wick. Furthermore, excess of vapor caused by over- 115 heating will cause a yellow and smoky streak in the flame and if the excess of generated vapor is sufficient, the flame turns from a blue smokeless flame to a yellow 120 smoky flame.

For the purpose of convenience in the claims, the outer member 10 will be referred to as a "deflector", and the inner member 11, as a "vertical flange."

125 My improved burner embodies an inner deflector C, and this deflector comprises a bowl-shaped member 27, which has a plurality (preferably three) outwardly combined supports and spacers 28, having shoul- 130

ders 29, which rest upon a suitable ring 30, attached to the inner side of the inner wick tube 2.

Located in the upper portion of this bowl member 27, is a disk 32, which is slightly concaved upwardly. This disk is smaller in diameter than the internal diameter of the bowl 21, and its periphery is provided with outwardly extending arms 33 (as shown in Fig. 4) the outer ends of which engage the member 27 near its upper end. This construction forms approximately an annular passage 34 between the periphery of the disk 32 and the inner wall of the bowl 27 near its upper end. A centrally arranged opening 35 is formed in the disk 32, and a centrally arranged opening 31 is formed in the bottom of the bowl-member 27. The opening 31 is much larger than the opening 35. The upper edge of the bowl 27 is slightly turned inward, as shown at 36, which performs the double function of permitting the flame to be deflected inward and of holding the disk in the wick-bowl.

By reason of this construction, substantially a ring of air is fed through the passage 34 to the interior of the flame, at a point above the upper inner end of the deflector member 10 of the outer distributor 30 B, and the opening 35 prevents any tendency to a vacuum over the disk 32, which vacuum would tend to draw the flame and vapor inward and disturb the uniformity of the flame and disturb the proper mixture 35 of the air within the interior of the flame.

Having thus described my invention, what I claim and desire to secure by Letters Patent is:—

1. A blue flame oil burner of the type described, comprising an inner and an outer wick tube, an air distributor within the inner wick tube at its upper portion, a chimney having its lower end surrounding the outer wick tube and an outer air distributor 45 located between the chimney and the outer wick tube, the outer air distributor consisting of only two members, viz., an inner vertically arranged annular flange surrounding but apart from the outer wick tube, and an outer deflector having its lower end at the lower end of the chimney, and its upper end curved inward over the upper end of said flange and the wick tubes and apart from them.

2. A blue flame oil burner of the type described, comprising an inner and an outer wick tube, an inner air deflector within the upper portion of the inner wick tube, a chimney having its lower end surrounding the outer wick tube and apart therefrom, and an outer air distributor within the lower end of the chimney and between it and the outer wick tube, the outer air distributor 60 consisting of two members only, viz., an inner annular vertical flange surrounding but

apart from the outer wick tube and extending thereabove, an air deflector between the said flange and the lower end of the chimney, the deflector extending upward and inwardly from the lower end of the chimney with its upper end above but apart from the upper ends of the flange and the wick tubes, the lower portion of the flange having horizontal air passages and the upper end of the deflector having vertical air 75 passages combined for the purpose described.

3. A blue flame oil burner of the type described, comprising inner and outer wick tubes; and a distributor within the upper portion of the inner wick tube, a chimney having its lower end surrounding but apart from the upper portion of the outer wick tube, an inner air deflector located between the chimney and the outer wick tube, the 80 inner air deflector consisting of an inner vertically arranged annular flange surrounding but apart from the outer wick tube, the outer wick tube having a horizontally outwardly projecting annular flange upon 85 which the lower end of the said vertical flange rests, an outer annular distributor member having its lower end connected with the lower end of the chimney and extending upward and inward with its upper portion 90 above but apart from the upper end of the flange and the wick tubes, the vertical flange having horizontal openings to the space between it and the outer wick tube, the upper end of the deflector member having 95 vertical openings, the parts combined 100 to operate for the purpose described.

4. A blue flame oil burner of the type described, comprising inner and outer tubes, an air distributor within the upper portion 105 of the inner wick tube, a chimney having its lower end surrounding but apart from the outer wick tube, and an outer air distributor consisting of two parts, viz., an inner vertically arranged annular flange 110 surrounding but apart from the outer wick tube, an outer annular deflector having a horizontal flange at its lower end extending outward to the lower end of the chimney, and the upper portion of the deflector 115 extending upwardly and inwardly over and apart from the upper ends of the flange and the wick tubes, the said horizontal flange having vertical openings to the spaces between the chimney and the deflector, the 120 said vertical flange having openings to the space between it and the outer wick tube and the upper portion of the deflector having vertical openings, the parts arranged for the purpose described.

5. A blue flame oil burner of the type described, comprising an inner and an outer wick tube, an outer air distributor surrounding and extending above the wick tubes, a chimney having its lower end sur- 130

- rounding but apart from the outer air distributer, and an inner air distributer within the inner wick tube, the inner air distributer comprising a downwardly extending bowl-shaped member having a disk within its upper portion, the lower end of the bowl-shaped member and the disk each having centrally arranged and vertically aligned openings.
- 10 6. A blue flame oil burner of the type described, comprising inner and outer wick tubes, a chimney, an outer air distributer between the chimney and the outer wick tube, an inner air distributer within the inner wick tube, said inner air distributer comprising a downwardly extending bowl-shaped member, a disk within the upper portion of the bowl-shaped member, the disk having central and peripheral passages, and the bottom 20 of the bowl having a vertical passage, the parts combined for the purpose described.
7. A blue flame oil burner of the type described, comprising inner and outer wick tubes, a chimney having its lower end 25 rounding but apart from the outer wick tube, and an outer air distributer between the lower end of the chimney and the upper end of the outer wick tube, and an inner air distributer located within the upper 30 portion of the inner wick tube, the inner distributer comprising a downwardly extending bowl-shaped member, a disk within the upper end of the bowl-shaped member and of a less diameter than the interior 35 diameter of the bowl, the disk having projecting supporting arms, whereby peripheral passages are provided, the bottom of the bowl-shaped member and the disk hav-

ing vertical passages, the parts combined for the purpose described.

8. A combined chimney and outer air distributer for a blue flame oil burner of the type described, comprising a chimney, an outer air distributer within the lower end of the chimney, the air distributer consisting of an annular vertical flange, an outer annular deflector extending upwardly and inwardly over but apart from the upper end of the vertical flange, spacing members connecting the flange and the deflector, the lower end of the deflector connected with and carried by the chimney, the vertical flange having horizontal openings, the deflector having vertical openings in its upper portion, the parts combined for the purpose 55 described.

9. A combined chimney and outer air distributer, for a blue-flame burner of the type described, comprising a chimney, an air distributer within the lower end of the chimney, the air distributer consisting of an inner vertically arranged flange and an outer deflector surrounding but apart from the flange, the upper end of the deflector extending upward and inward above the upper edge of the flange, the lower end of the deflector connected with the chimney and the flange connected with the deflector by spacers extending below the lower end of the flange, and the inner edges of the extended ends forming positioning members, as shown.

In testimony whereof I hereunto affix my signature.

ARTHUR STOCKSTROM.
